UNITED STATES PATENT OFFICE

CHARLES E. SPIGELMIRE, OF SPARROWS POINT, AND ROBERT M. WALTERS, OF DUNDALK, MARYLAND, ASSIGNEES TO BETHLEHEM STEEL COMPANY, A CORPORATION OF PENNSYLVANIA

PROCESS FOR REMOVING DEFECTS FROM METAL BODIES

Application filed December 12, 1930. Serial No. 501,898.

Our invention relates to a process for removing defects from metal bodies.

As is well known, steel blooms, slabs and other preliminary shapes of steel or iron, frequently have surface defects such as crevices, cracks and the like. To roll a bloom or slab without removing these surface imperfections would result in imperfect products. The mechanical working, such as rolling, involving a kneading like manufacture, would cause the surface defects to become incorporated more deeply in the metal mass with consequent weaknesses and defects of the steel structure. Accordingly it has been the prevailing practice to remove these surface defects from the blooms or slabs by chipping. An operator with a pneumatic chipping hammer progressively chips away the surface metal which contains the defects. Necessarily this is a slow process and involves a very substantial cost for labor.

Our process consists in removing the defects by burning away the metal which contains it instead of by chipping it off.

Obviously it is not broadly new with us to burn or, as is more commonly called, "cut" metal but, so far as we know, it is novel with us to remove imperfections in the surface of metal bodies by burning away the surface metal containing the imperfections.

Our method consists in directing a stream of oxidizing gas onto the surface of the metal to burn away the surface metal which includes the defect. An important feature of our method is in so burning away the portion of the metal containing the defect as to produce a depression which merges gradually into the surrounding unburned metal, that is to say, a depression which gradually diminishes in depth toward the surrounding unburned metal; contrasting with the ordinary "cutting" effects where a kerf is produced which does not taper off gradually in depth but is more or less abrupt having "steep" sides. If in removing defects kerfs were to be formed, as in the ordinary cutting operations, with the sharply abrupt sides, it would be difficult, if not impossible, to prevent the edges of the kerfs being folded over the cuts

during the rolling operations and defects thus produced in the metal structure.

In this application we shall set forth one mode of operation whereby these desirable, shallow, and gradually curving depressions may be produced. This particular way of doing this, here shown, involves the use of a flaring stream of oxygen which, when applied to the surface metal containing the defect produces its most intense burning action centrally thereof gradually diminishing outwardly therefrom whereby the gradually rounded depression in the metal is produced. This flaring stream of oxygen for burning out the defects is conveniently produced by passing the oxygen through a burner tip, the oxygen passageway of which flares or widens as it approaches the surface.

Referring to the drawing, which illustrates a tip which is suitable for this purpose:

Fig. 1 is a longitudinal section through the tip, taken on the line 1-1 of Fig. 2; and

Fig. 2 is an end view of the tip.

This tip includes the body portion 11 and the screw threaded shank portion 12 whereby the tip may be screwed to a blow torch in the well known way.

Extending centrally and longitudinally of the tip is the oxygen passage 13 having a flaring portion 14. Disposed around the oxidizing gas passage is a plurality of passageways 15 through which a mixture of combustible and oxidizing gas may pass as, for example, oxygen and acetylene.

This tip may be attached to a blow torch in the usual way, oxidizing gas passage 13 communicating with the oxygen passage of the torch and gas mixture passages 15 communicating with the gas passages thereof.

The torch may be employed in the customary way so far as the control and use of oxygen and fuel gasses are concerned. The distinctive characteristic of the tip is the flaring portion of the oxidizing gas passageway at its outer end, whereby the stream of oxygen as it issues from the tip widens and thereby produces a less intense effect marginally of the stream. As a consequence the metal is burned away in amounts gradually diminishing outwardly from the central por-

tions of the oxygen stream. Naturally this avoids the sharp edges which are produced by cutting with the means heretofore employed.

- 8 In burning away the surface metal, which includes the defect, the stream of oxygen is directed against the metal surface in a direction inclined thereto. If a seam, for example, is being removed, the torch is so held
10 that the stream of "cutting" oxygen issuing from this tip is inclined to the surface of the metal and substantially in line with the direction of the seam. In view of the fact that the stream of oxygen flares or widens,
15 the effects of the burning stream diminishes gradually in amount toward the adjacent unburned metal, thus producing a relatively wide, shallow depression which diminishes gradually in depth toward its sides.
20 Having thus described our invention what we claim as new and desire to secure by Letters Patent is:
1. In a process for removing imperfections from metal, the steps of heating the metal to
25 a kindling temperature and directing oxygen onto the surface of the heated metal to burn away the metal including the imperfect structure; such burning diminishing gradually in amount toward the adjacent un-
30 burned metal surface.
2. In a process for removing imperfections from metal, the steps of heating the metal to a kindling temperature and directing oxygen onto the surface of the heated metal to burn away the metal including the imperfect structure to produce a shallow depression diminishing gradually in depth toward its sides.
3. In a process for removing seams and
40 like defects from metal, the steps of heating the metal to a kindling temperature and directing oxygen in a flaring stream on to the surface of the heated metal at an inclination to the surface of the metal and in the
45 general direction of the seam.

In testimony whereof we hereunto affix our signatures.

CHARLES E. SPIGELMIRE.
ROBERT M. WALTERS.
